PATRICK D. SKAHEN, OF SYRACUSE, NEW YORK.

BURIAL-CASE.

1,071,105.

Specification of Letters Patent.

Patented Aug. 26, 1913.

Application filed December 12, 1906. Serial No. 347,460.

To all whom it may concern:

Be it known that I, PATRICK D. SKAHEN, of Syracuse, in the county of Onondaga and State of New York, have invented a certain 5 new and useful Burial-Case, of which the following is a specification.

My invention relates to burial-cases having removable covers, and has for its object the production of clamping means for the 10 covers, which is particularly simple in construction and highly effective in use; and to this end it consists in the novel combinations and constructions hereinafter set forth and claimed.

15 In describing this invention, reference is had to the accompanying drawing in which like characters designate corresponding parts in all the views.

Figure 1 is a sectional view of a portion 20 of a burial-case, one of its clamps being shown in elevation. Fig. 2 is an elevation, partly in section, of the means illustrated in Fig. 1. Fig. 3 is a face view of the detached clamp seen in Figs. 1 and 2, portions 25 of the case being shown as engaged by said clamp. Fig. 4 is a view similar to Fig. 1, a modified construction of clamp being illustrated.

1 and 2 are, respectively, the body, and 30 the cover of a burial-case. The body 1 is provided with an outwardly-extending flange 3 preferably formed by bending the metal at the upper part of the body outwardly, downwardly, and inwardly. Said 35 cover rests upon, and is supported by, the flange 3, and is provided with a depending flange 4 engaged with the outer edge of said flange 3. The cover 2 is held in position by a plurality of clamps of similar construction, each comprising two elements, one 40 a base 5 fixed to the body 1 beneath the flange 3, and the other a clamping member 6 adjustable relatively to the base 5 and co-acting with the upper surface of the cover 45 2. An arm 7 projects laterally from the base 5 beneath the flange 3, and is provided with an upturned extension 8 which is arranged at the outer side of a line perpendicular to the outer edge of the flange 3, said 50 extension projecting above the flange 3, and being formed with a threaded upper end 9. Said base 5 is formed with an extension 10 projecting above the arm 7 and increasing upwardly in width, the upper edge 11 of the extension 10 being engaged

with the lower face of the flange 3. A rivet or other securing means 12 is passed through the lower part of the base 5, and the opposing portion of the wall of the body 1, and serves to securely hold the base 5 in position, 60 this result being facilitated by the engagement of the relatively long edge 11 with the lower face of the flange 3. The clamping member 6 is arranged above the cover 2, substantially parallel to the arm 7, and one 65 end of the clamping member is formed with an internally-threaded eye 13 which receives the circular threaded end or part 9, and the other end of said member is formed with an upturned finger-piece 14. The portion 70 of the clamping member directly above the extension 10 of the base is provided with a lug 15 movable eccentrically relatively to the axis of the clamping member and formed with an inclined face 16 arranged at an 75 angle to, and coacting with, the portion of the surface of the cover 2 directly above the extension 10, such clamping face being spaced apart from the axis of the spindle 8 and eye 13, and movable eccentrically relatively to said axis. By turning the clamping member in opposite directions, the face 16 is forced into, and out of, engagement 80 with the cover for clamping and releasing the same.

85 In the preferable construction of this invention, the extension 8 inclines upwardly in one direction toward the opposing surface 17 of the body 1, as seen in Fig. 1, and inclines upwardly in another direction toward the surface 18 of the body disposed at substantially a right angle to the surface 17 as illustrated in Fig. 2. In other words the spindle 8 inclines upwardly toward the body and in the direction of the turning movement of the member 6 into operative position. The extension 8 thus inclines in two directions relatively to the opposing surfaces of the body 1 and the cover 2. When the clamping member 6 is moved from the 90 outer side of the burial-case into operative position, as indicated in Fig. 1, the inclination of the extension 8 causes the face 16 to approach the upper surface of the cover 2 more quickly than would otherwise be the 95 case, and to bind against the same to a maximum extent. As indicated in Fig. 4, instead of forming the threaded extension of the clamp upon the base 5, it may be provided upon the clamping member, and the in- 100 105 110

ternally-threaded eye for receiving such extension may be formed in the free end of the arm 7 projecting laterally from said base.

What I claim is:—

- 5 1. In a case the combination with a body and a cover; of a clamp comprising two elements, one a base fixed to one of the parts of the case and the other a clamping member movable toward and from the other of the 10 parts of the case, one of said elements having an upright threaded spindle spaced apart from the body and the other having a threaded eye for receiving the spindle, the clamping member being movable about the 15 axis of the spindle and eye into and out of operative position and having an engaging face spaced apart from said axis, substantially as and for the purpose described.
- 20 2. In a case, the combination with a body and a cover; of a clamp comprising two elements, one a base fixed to one of the parts of the case, and the other a clamping member movable toward and from the other of the 25 parts of the case, one of said elements having an upright threaded spindle spaced apart from the body and the other having a threaded eye for receiving the spindle, the spindle and said eye being arranged with their axes inclining out of a vertical plane 30 toward the body and in the direction of turning movement of the clamping member into operative position, the clamping member being movable about the axis of the spindle and eye into and out of operative 35 position and having an engaging face spaced apart from said axis, substantially as and for the purpose described.
- 40 3. In a case, the combination with a body and a cover; of a clamp comprising a base fixed to the body and provided with a lateral arm, and a clamping member for the cover movable toward and from the cover, the clamping member being normally arranged in a plane substantially parallel to the arm, 45 and the clamping member and the arm being

connected by a threaded spindle associated with one of the connected parts and an eye for receiving the spindle formed in the other of the connected parts, the spindle being inclined out of a vertical plane toward the 50 body and in the direction of the turning movement of the clamping member into operative position, and the clamping member being movable about the axis of the spindle and the eye toward and from the cover and 55 having an engaging face which moves eccentrically to the spindle, substantially as and for the purpose specified.

4. In a case, the combination with a body and a cover, of a clamp comprising two elements, one a base fixed to one of the parts of the case, and the other a clamping member movable toward and from the other of the parts of the case, one of said elements having an upright threaded spindle spaced 60 apart from the body and the other having a threaded eye for receiving the spindle, the spindle and said eye being arranged with their axes inclining out of a vertical plane 65 toward the body and in the direction of the 70 turning movement of the clamping member into operative position, the clamping member being movable about the axis of the spindle and eye into and out of operative 75 position and having an engaging face spaced apart from said axis which face moves eccentrically to the spindle, such engaging face being inclined out of a plane parallel 80 to the surface with which such engaging face coacts, substantially as and for the purpose set forth.

In testimony whereof, I have hereunto signed my name in the presence of two attesting witnesses, at Syracuse, in the county of Onondaga, in the State of New York, 85 this 8th day of December, 1906.

PATRICK D. SKAHEN.
